UNITED STATES PATENT OFFICE.

CHARLES OSBORNE, OF NORTH ATTLEBOROUGH, MASS., ASSIGNOR TO
THE WHITING MANUFACTURING COMPANY, OF NEW YORK, N. Y.

DESIGN FOR BORDER FOR SILVER-WARE.

Specification forming part of Design No. 7,622, dated August 4, 1874; application filed June 29, 1874.
[Term of Patent 7 years.]

CASE A.

To all whom it may concern:

Be it known that I, CHARLES OSBORNE, of North Attleborough, Bristol county, in the State of Massachusetts, have invented a new and original Design for Border for Silver-Ware and analogous goods, of which the accompanying drawing or photograph, with this specification, is a full and complete description.

The drawing is a face view of a short length of the border, shown on a dark ground. The center and main portion of the border is formed by a series of tracery in cameo, formed by a repetition of curved fillets, *b*, with leaves *d*. The ends are formed with gracefully-rounded swells or knobs *a* and *c*, and from the leaves *d* projects a slight curved fillet with a corresponding knob, *d'*. The scrolls are interwoven, as shown, and surmounted at the central crossing-points by concentric circles formed by beads *g h*. Above and below the main surface or bordure thus decorated is a narrow dotted or berried bead, *i*, and beyond this a rectangular or slightly-rounded bead, *j*.

The pattern or design may be varied in size, and in the precise arrangement of the details, so long as they form essentially the same design and produce the same ornamental and distinctive effect.

What I claim as my design for border is—

1. The circular ornaments *g h* and interwoven tracery *b*, as shown and described.
2. The knobbed or swelled ends *a c*, tracery *b*, and leaves *d*, with the superposed ornaments *g h* at the crossing-points, as shown and described.
3. The curved fillets or tracery *a b c*, surmounted by circular ornaments *g h* and inclosed within the beads *i j*, as shown and described.

In testimony whereof I have hereunto set my hand this 25th day of June, 1874, in the presence of two subscribing witnesses.

CHARLES OSBORNE.
